VERKSTED, OF CHRISTIANIA, NORWAY.

OVERLOAD SWITCH.

1,403,217.

Specification of Letters Patent. Patented Jan. 10, 1922.

Application filed November 10, 1921. Serial No. 514,368.

To all whom it may concern:

Be it known that I, HANS WILLMANN, a German subject, residing at Lütticherstrasse 50, Berlin N. 65, Germany, have invented 5 certain new and useful Improvements in Overload Switches; and I do hereby declare the following to be a full, clear, and exact description of the invention, such as will enable others skilled in the art to which it 10 appertains to make and use the same, reference being had to the accompanying drawings, and to letters or figures of reference marked thereon, which form a part of this specification.

15 The present invention relates to improvements in maximum overload switches; and its principal objects are: first, to construct the switch and its various component parts in such a manner as to save space, and, second, to avoid the danger of breakage of parts due to careless operation.

Heretofore, maximum overload switches which are designed to carry continuous small overloads and which are also adapted to 25 carry momentary overloads of greater extents, have usually had to be made comparatively large with relation to switches designed for sustained higher overloads, the reason being that the operating devices must 30 be heavy in order to withstand the stresses put upon them, so that a certain size is accordingly required for each part. Also, it is well known that when the switch is in charge of an inexperienced person, such person is 35 very likely, in spite of his instructions, to turn the handle of the switch in the wrong direction, which may cause breakage of the stop parts, unless the latter be made so strong that they can withstand any stresses imposed 40 upon them under such conditions. This likewise results in the size of the switch parts having to be increased.

According to the invention, the usual operating handle is replaced by one which, instead of being movable in one direction only 45 to open the switch, can be moved in either direction with equal facility. When the circuit is closed, it can be opened manually by moving the handle of the switch in either 50 direction, irrespective of the automatic circuit-breaking operation; and conversely, when the circuit is open, it can be closed by moving the switch handle in one direction or the other. To effect this object, the switch 55 handle preferably consists of a button or the

like which may be rotated either to the right or to the left.

An embodiment of the invention is illustrated in the accompanying drawing, in which:

60 Figures 1 and 2 are front and side views, respectively, showing the parts of the switch in circuit-closing position.

Fig. 3 is a front view showing the position assumed by the parts when the switch 65 is operated manually to open the circuit.

Fig. 3^a is a side view of a detail.

Fig. 4 is a side view showing the position of the parts after an automatic operation of the switch to open the circuit.

70 Fig. 5 is a diagram of the electrical connections.

Fig. 6 is a front view of the invention as applied to a bi-polar switch.

Fig. 7 is a diagram of the electrical connections of the bi-polar switch.

Referring more particularly to the drawing, the improved overload switch comprises a suitable magnet, the core of which is indicated at *a*^k and the winding at *v*; the magnet 80 also having associated with it an armature *A*. Current is supplied to the usual contact brushes *K'* through wires which are connected to the device at *F*₁ and *F*₂; said brushes *K'* being engageable with the fixed 85 contact *K* to close the circuit and being provided with suitable spark quenchers *g*. These brushes are carried by pivoted switch arms or levers *K*² which are pivoted at their lower ends to a toggle *l*, the component members of which are disposed in alinement 90 when the circuit is closed, but swing downward incidental to the circuit breaking operation and in so doing pull the lower ends of the switch levers *K*² inward, thereby 95 moving their upper ends away from each other and, in consequence, disengaging the contact arms or brushes *K'* from contact *K* and separating the two spark quenchers *g*.

The toggle arms or members are made sufficiently heavy to enable this break-joint action to be effected automatically under certain conditions, as hereinafter explained; but normally said members are held in their alining position by means of a hook *h* 100 which is pivoted to them at their point of connection and is engaged with the hooked lower end *m'* of a vertical slide *m* suitably connected to the body or frame *F* of the device. The hook *h* has pivoted to it a hor- 110

izontal link h^2 terminating in a hooked rear end h^3 which is engagable by the lower end of the armature A, the latter being pivotally supported in rearwardly-inclined position by 5 the aforesaid frame or body F.

Adjacent one of the plates F which form the frame or body, there is arranged the vertical slide m above referred to, which is provided with a pair of spaced, alining vertical slots m^2 and with a central, rectangular opening u between said slots, these slots forming guides through which projects a pair of lateral pins m^3 fixed to plate F. The central opening u is designed to receive 10 therein a cross-piece b, which is secured to the stem of a rotatable operating button a connected to the magnet core a^k , as indicated in Fig. 3^a; the height of said opening and the length of said cross-piece corresponding 15 to the extent of movement which is desired for the break-joint or toggle l. This button and its cross-piece constitute a manual means or device for operating the switch, the movement of the cross-piece serving to raise and 20 lower the controller slide m.

The operation is substantially as follows, assuming that the parts are in the circuit-closing position represented in Figs. 1 and 2, with the arms or brushes K' engaging 25 contact K, the slide m and toggle l raised, the hooks h and h' engaged and the cross-piece b upright in opening u. If it is desired to open the circuit for any reason, the button a is given a quarter-turn in either 30 direction, so as to move cross-piece b into horizontal position as indicated in Fig. 3. Slide m is no longer supported by said cross-piece and, therefore, drops and exerts 35 its weight against the break-joint or toggle, which latter acts to rock the switch levers K² so as to separate the brushes from contact K and thus break the circuit. The hooks h and h' remain engaged during the 40 downward movement of the slide, because the armature A is not attracted at this time 45 and, hence, does not shift link h^2 rearward to release hook h.

In the case of a maximum overload, however, and again assuming that the parts are 50 positioned as in Figs. 1 and 2, the magnet will attract its armature A, which will swing inward or to the right in Fig. 2, and in so doing, will pull link h^2 rearward and uncouple the two hooks. The toggle will 55 then break of its own weight, and, in consequence, will operate the switch levers to open the circuit in the manner previously described. The button a is not operated in effecting this action, which is entirely automatic 60 and occurs only when the maximum overload is passing through the line; whereas the operation first described is entirely manual, and may be effected at will by merely turning the button in one direction 65 or the other. In the second or automatic

operation, therefore, the cross-piece b remains in its vertical median position, and thus prevents the slide m from falling. In both cases, however, the parts may be returned to normal position by suitably manipulating the button. 70

The development or modification illustrated in Figs. 6 and 7 relates to the application of the invention to bi-polar overload switches. Switches of that character, as is well known, generally require double, or nearly double, the space of a single-pole switch; but according to my invention, such defect is overcome by substituting for the contact K a divided contact k^2 , the two parts or members of which are separated by a layer k^3 of insulating material. The conducting wires are connected at F₁, F₂ and F₃, F₄, respectively, and the operation is the same as that previously described. 80

I claim as my invention:—

1. In an overload switch, the combination of movable contact-carrying means; a vertically-movable slide for moving the contact-carrying means into and out of circuit-closing position, said slide and said contact-carrying means moving relatively to each other at such time; and a handle rotatable at will in either direction to operate said slide. 90

2. In an overload switch, the combination of movable contact-carrying means; a vertically-movable slide for moving the contact-carrying means into and out of circuit-closing position, said slide and said contact-carrying means moving relatively to each other at such time; and a handle rotatable at will in either direction and provided with a cross-piece cooperative with said slide to shift the same and thereby operate said contact-carrying means. 100

3. In an overload switch, the combination of movable contact-carrying means; a controller for moving the contact-carrying means into and out of circuit-closing position, said contact-carrying means and said controller moving relatively to each other at such time, said controller having a rectangular opening; and a handle rotatable at will in either direction and provided with a cross-piece arranged in said opening to operate said contact-carrying means. 110

4. An overload switch, comprising movable contact-carrying means; means for automatically moving the contact-carrying means to circuit-breaking position when an overload occurs; and manual means rotatable at will in either direction to move said means to said position. 120

5. An overload switch, comprising a pair of movable switch arms; a toggle to which said arms are pivotally connected, said toggle acting to move said arms to circuit-breaking position; electro-magnetic means for automatically effecting the operation of 130

the toggle when an overload occurs; and manual means for effecting the operation of the toggle at will.

6. An overload switch, comprising a pair of movable switch arms; a toggle to which said arms are pivotally connected, said toggle acting to move said arms to circuit-breaking position; electro-magnetic means for automatically effecting the operation of the toggle when an overload occurs; and manual means rotatable at will in either direction to effect the operation of the toggle.

7. An overload switch, comprising a pair of movable switch arms; a toggle to which said arms are pivotally connected, said toggle acting to move said arms to circuit-breaking position; a slide arranged to bear upon said toggle to operate the same; and a manual device associated with said slide to normally hold it in inactive, raised position but operable at will to enable the slide to drop and thereby cause the toggle to move the switch arms to break the circuit.

8. An overload switch, comprising a pair of movable switch arms; a toggle to which said arms are pivotally connected, said toggle acting to move said arms to circuit-breaking position; a slide arranged to bear upon said toggle to operate the same; and a manual device associated with said slide to normally hold it in inactive, raised position but rotatable at will in either direction to release the slide and thereby permit it to drop and actuate the toggle.

9. An overload switch, comprising a pair of movable switch arms; a toggle to which said arms are pivotally connected, said toggle acting to move said arms to circuit-breaking position; a slide arranged to bear upon said toggle to operate the same, said slide having a rectangular opening; and a handle rotatable at will in either direction and provided with a cross-piece arranged in

said opening to normally hold the slide in inactive, raised position, but releasing the slide consequent upon the rotation of the handle.

10. In a bi-polar overload switch, the combination of a contact comprising a pair of separate members with insulation between them; a pair of switch arms disposed at opposite sides of said contact members for cooperation with the same; electro-magnetic means for automatically moving the switch arms in opposite directions away from the contact members when an overload occurs; and a device movable manually at will in either direction for moving said switch arms in opposite directions away from said members.

11. In a bi-polar overload switch, the combination of a contact comprising a pair of separate members with insulation between them; a pair of switch arms disposed at opposite sides of the contact members for cooperation with the same; and a handle rotatable at will in either direction to move said switch arms in opposite directions away from said members.

12. In a bi-polar overload switch, the combination of a contact comprising a pair of separate members with insulation between them; a pair of switch arms for cooperation with said members; a toggle to which said arms are pivotally connected; and a handle rotatable at will in either direction to operate said toggle and thereby rock said arms out of engagement with said members.

In testimony that I claim the foregoing as my invention, I have signed my name in presence of two subscribing witnesses.

HANS WILLMANN.
